WAVE MOTOR DEVICE

Charles A. Webber, Brooklyn, N. Y.

Application October 8, 1932, Serial No. 636,821

9 Claims. (Cl. 253—11)

This invention relates to wave motor devices and has for its object the provision of a wave motor device which is adapted to be operated with a minimum degree of wave motion.

Another object of the present invention is to provide a wave motor device adapted to produce a continuous flow of power without the necessity of providing means to store the wave motor energy.

Another object of the present invention is to provide a simple, efficient and inexpensive wave motor device.

Other objects and advantages will become apparent as the invention is more fully disclosed.

In accordance with the objects of the present invention, I have devised an assembly of elements comprising the wave motor device in which a fulcrumed arm is supported upon a suitable pier or wharf extending out over the water from the shore line a suitable distance; the short end of the arm extending out over the water and the longer end thereof extending shoreward.

A float element is attached to the shorter lever arm and the other end of the lever is adapted to operate suitable air or water pumping or electric generating mechanism with a vertical rise and fall of the lever, the effluent of said pump mechanism being conveyed away to operate power generating apparatus; or said lever and float directly operating said generating apparatus; all as will be more fully hereinafter disclosed.

The invention is illustrated in the accompanying drawing wherein an apparatus for generating electricity directly by the wave motor device of the present invention is shown diagrammatically.

In my present invention, a wave motor similar to that of my pending application Ser. No. 574,293 filed November 11, 1931, is used, but instead of operating a pump as in said application, the power from the motor is applied directly to an electric generator.

Referring to the drawing, the lever 1 is fulcrumed at 2 on a pier or wharf 3 and carries upon its shorter arm 4 a float 5 so positioned as to rest on the surface of a body of water from which the wave impulses are received. The other arm 6 of the lever extends shoreward a length greater than that of the arm 4 so that a relatively small vertical movement of the arm 4 resolves itself into a relatively large vertical movement at the end of the longer arm 6. The power generated in this movement is utilized in the present invention directly for the generation of electric power.

To operate a generator of electricity, a high speed is usually required. For this purpose, therefore, the power at the end of the lever arm 6 is transmitted through a speed multiplying means to the electric generator. The speed multiplying means comprises a train of gears or a belt train and a means for changing the reciprocating movement of the end of the lever arm into a unidirectional rotation of the wheel or belt train.

For this purpose the end of the lever 6 is slotted at 7 and is provided with a pin 8 slidable in this slot. The end of the lever arm 6 is guided between suitable guides 9. The cable 10 is trained over a pulley 11 mounted at the upper end of the guides 9 and at one side of said pulley depends past and is secured to the pin 8 so that as the lever 1 rocks about the fulcrum 2 the pin 8, and with it the cable 10, is given a reciprocating vertical movement.

That part 12 of the cable 10 that hangs from the opposite side of the pulley 11 is given an equal and opposite reciprocating movement. The cable length 10 passes downwardly about a guide pulley 13 and near its lower end is secured to a rock arm 14.

A weight 15 is secured to the lower end of the cable 10 below the rock arm 14. The cable length 12 passes about a pulley 16 and thence upwardly. In its upward passage it is connected to a rock arm 17 and extends past this rock arm over a pulley 18 and thence downwardly.

A weight 19 is attached to the downwardly hanging end of the cable length 12. The rock arms 14 and 17 are secured by a link 20 so that they rock uniformly in the same direction. The connection between the cable length 10 and the rock arm 14 is such that at the first portion of the upward movement of the lever arm 6, the arm 14 swings to the left to carry a portion of the cable 10 into engagement with the teeth of a sprocket wheel 21, the cable being provided at this part of its length with sprocket-engaging loops or means. The further continued movement of the cable length 10 thereupon causes a counter-clockwise rotation of the sprocket wheel 21. As the lever arm 6 rocks downwardly, the first movement of the arm 14 is outwardly to release the cable 10.

Similarly, when the arm 14 is moved by the initial downward movement of the cable 10 it swings the arm 17 clockwise so as to bring a part of the cable length 12, passing upwardly between the pulleys 16 and 18, into contact with the opposite side of the sprocket wheel 21. As this part

of the cable length 12 is moving downwardly at this time, it also serves to rotate the sprocket wheel 21 counter-clockwise.

Similarly the initial movement of the rock arm 5 17 serves to release the cable length 12 from the sprocket wheel.

The arrangement is such that one cable length just clears the teeth of the sprocket wheel as the other moves into engagement therewith.

10 As a result of this mechanism, the sprocket wheel 21 is given a counter-clockwise movement with each up-swing and down-swing of the lever arm 6, and the movement of the wheel is not only unidirectional, but substantially continuous, provided the lever arm 6 is always in movement.

15 The sprocket wheel 21 is connected to a larger pulley or sprocket 22, either by a ratchet connection or, if desired, a suitable ratchet and pawl device 23.

20 The power of the rotating sprocket wheel 22 is transmitted with increased speed through a sprocket chain 24, sprocket wheels 25 and 26, chain 27 and sprocket wheel 28 to a generator 29.

25 It will be understood that additional or lesser numbers of sprocket wheels and chains may be employed, and that other equivalent trains may be used if desired.

30 It will also be understood that two or more sets of levers 6 may be employed, and that to secure continuity of motion, several wave motors may be connected through suitable ratchet and pawl means to a single gear train, thus giving a more constant and continuous power and speed to the generating mechanism.

35 From the above description and drawing it is believed clear that the wave motor device of the present invention is adapted to be operated under conditions where there is a minimum wave height and therefore singularly free from periods of inactivity due to periods of calm or wave inactivity.

40 Heretofore in the art wave motor devices have been dependent upon a relatively large rise and fall of the waves at the point of installation. In periods of calm the efficiencies of these prior art wave motor devices have fallen. In the present invention periods of calm will have relatively little effect upon the efficiency of the wave motor device

45 and the device may be installed in places where the average rise and fall of the wave is relatively low and where the same may be protected from the unusual conditions incident to storms, floods and the like. Moreover, it is believed clear from the above description and drawing that the wave motor device of the present invention is operative irrespective of variations in the tide level of

50 the body of water and also operative with substantial equal efficiency at any given wave height and through a relatively wide range of varying wave heights. The general adaptability and utility of the present invention thereby is greatly enlarged.

Having described the invention, what I claim is:

1. A wave motor device comprising a fulcrumed lever having a short arm and a long arm, means to support said lever with the short arm extending out over water, a float element rigidly attached to the end of said short lever arm and means to directly translate the vertical rise and fall of said long lever arm incident to wave motion acting upon said float to the generation of power irrespective of variations in the tide level of said water and with substantial equal efficiency at any given wave height.

70 2. In a wave motor device of the type described

and claimed in claim 1, motion translating means comprising means for changing the reciprocating movement of the end of the lever arm into a unidirectional rotation of a wheel and speed multiplying means operatively connected between said wheel and power generating apparatus.

80 3. In a wave motor device of the type described and claimed in claim 1, a cable, means for giving said cable a reciprocating motion from said long lever arm, a sprocket wheel and means for bringing alternate lengths of said cable into engagement with a sprocket wheel with alternating movements of said long lever arm thereby to impart a unidirectional movement to said sprocket wheel.

85 4. In a wave motor device of the type described and claimed in claim 1, a cable, means for giving said cable a reciprocating motion from said long lever arm, a sprocket wheel, means for bringing alternate lengths of said cable into engagement with a sprocket wheel with alternating movements of said lever arm thereby to impart a unidirectional movement to said sprocket wheel and an electric generator and speed multiplying means between said sprocket wheel and said electric generator.

90 5. In a wave motor device of the type described and claimed in claim 1, a cable secured to the long arm of said lever, a sprocket wheel, pulleys on which said cable is trained so as to cause a length of said chain to move upwardly during the up-stroke of said lever arm and another part of said cable to move downwardly during the down-stroke of said lever arm and means to bring the lengths in contact with the sides of said sprocket wheel.

95 6. In a wave motor device of the type described and claimed in claim 1, a cable secured to the long arm of said lever, a sprocket wheel, pulleys on which said cable is trained so as to cause a length of said chain to move upwardly during the up-stroke of said lever arm and another part of said cable to move downwardly during the down-stroke of said lever arm, means to bring the lengths in contact with the sides of said sprocket wheel and a belt train driven from said sprocket.

100 7. In a wave motor device of the type described and claimed in claim 1, a cable secured to the long arm of said lever, a sprocket wheel, pulleys on which said cable is trained so as to cause a length of said chain to move upwardly during the up-stroke of said lever arm and another part of said cable to move downwardly during the down-stroke of said lever arm, means to bring the lengths in contact with the sides of said sprocket wheel and speed multiplying devices driven from said sprocket.

105 8. In a wave motor device of the type described and claimed in claim 1, a cable secured to the long arm of said lever, a sprocket wheel, pulleys on which said cable is trained so as to cause a length of said chain to move upwardly during the up-stroke of said lever arm and another part of said cable to move downwardly during the down-stroke of said lever arm, means to bring the lengths in contact with the sides of said sprocket wheel, speed multiplying devices driven from said sprocket and a pawl and ratchet between said sprocket wheel and said speed multiplying devices.

110 9. In a wave motor device of the type described and claimed in claim 1, motion translating means comprising vertical guide members positioned adjacent the end of the long lever arm and on
